CLAIM

The ornamental design for a computer, as shown and described.

DESCRIPTION

1.-2. Computers
1.1 : Perspective
1.2 : Perspective
1.3 : Front
1.4 : Back
1.5 : Left
1.6 : Right
1.7 : Top
1.8 : Bottom
2.1 : Perspective
2.2 : Perspective
2.3 : Front
2.4 : Back
2.5 : Left
2.6 : Right
2.7 : Top
2.8 : Bottom

(Continued)

A combined computer and base for a monitor; the broken lines shown in the drawings represent portions of the computer that form no part of the claimed design.

1 Claim, 16 Drawing Sheets
